MEAT SAW CRADLE

John C. Gonser, Lansing, Mich.

Application April 3, 1942, Serial No. 437,570

1 Claim. (Cl. 146—88)

This invention relates to meat saw cradles which are parts of the machines constructed to slice meats and the like, the cradle being the member carrying the material to be cut or sawed.

The object of this invention is the special construction of the cradle and the manner of its support upon the meat sawing machine, whereby it is believed the work of cutting meat and meat products may be easily and conveniently performed, the construction being of simple character in its formation and operation, and inexpensive.

In the accompanying drawings the particular structure and disposition of the elements of this invention are illustrated, and

Fig. 1 shows the front view of a meat saw and exhibits all parts of this invention in usable position.

Fig. 2 is a side view of the parts set forth in Fig. 1.

Fig. 3 represents a top plan view of the table showing the slot and holes or the like for the adjustment and locking of the sliding thickness gauge.

Fig. 4 is a top plan view of the cradle.

Fig. 5 is a side view of the sliding thickness gauge, showing the securing and locking pegs.

Fig. 6 represents a sectional view of the cradle taken on the line 6—6 of Fig. 4.

Throughout the drawings and description the same number is used to refer to the same part.

In Figs. 1 and 2 a base 1 is shown for a saw machine having operating belt 2. The sawing or cutting details are not illustrated, as they form no part of this invention. A machine supporting post or the like 4 bears the table 5, and in Fig. 3 the slots 6 and pin holes 7 are shown for locking the gauge mentioned hereinafter. The slot 8 is ordinarily formed and positioned to secure the table to the machine frame or supporting members. The T-form of slot 8 shown in Fig. 3 is used to engage an ordinary bolt to prevent displacement of table 5 in any direction. The particular T-form shown is not a part of the invention. The lower side portion 9 and the like upper side casing 10 are connected by the portion 11 of the supporting machine structure.

In Fig. 1 the number 12 marks a projecting arm, usually a cylindrical piece as shown, and upon the arm is pivotally connected the upper end of the suspending strip 13 that is provided with a curving lower portion secured externally to the larger and wider portion 14 of the cradle proper, which is constructed to carry the meat to be sawed. It will be noted in Fig. 4 that the larger and wider portion 14 of the cradle has an integral and relatively narrower and smaller side exten-

sion 15. This affords space in the cradle to permit the operator to easily and conveniently handle the meat borne by the cradle. It is particularly advantageous when the piece of meat is of large size and correspondingly heavy.

To permit slices of different thickness to be cut, the sliding thickness gauge 16 is constructed as shown in Fig. 5. It is braced by the inclined side pieces 17 extending from the gauge plate 16 to the sliding bottom 18. The bottom is made with the locking pegs 19 and pins 20 adapted to engage the slot 6 and pinholes, or other slots, 7, to enable the cutter to slide the gauge to any desired position upon the table 5 to control the thickness of the slice of meat cut away.

In Figs. 1 and 2 it will be observed that the bracket 21 from which arm 12 projects is carried by the vertically adjustable rod 22 which passes through a suitable holder 23 on the machine supporting structure and is provided with a thumb screw 24 to fix the rod in position after it has been adjusted.

The operation of this invention is thought best observable from Fig. 1, taken in connection with Fig. 2. It is thought to be made clear that the cradle may be swung outward and inward during the sawing process, and that the meat to be cut can be slipped along the larger curving portion of the cradle towards the thickness gauge, permitting a slice of any desired thickness to be cut away. The simplicity of the special construction of this invention is believed to enable the machine to be more easily and quickly cleared and cleaned after use, than is practicable in any other like apparatus with which I am acquainted.

Having now described this invention, I claim:

A meat saw cradle, in combination with a base having a supporting post, a horizontal table carried by the post, said table having a series of pin holes and slots, a thickness gauge adapted to rest movably upon the table and provided with pins and pegs at the bottom of the gauge whereby its position on the table may be variously arranged and secured by said pin holes and slots, a vertically adjustable rod carried by the supporting post and a screw device for holding the rod in place, a bracket arm attached to the upper end of the rod, a projecting member attached to the bracket to carry the cradle, a strip movably engaging said member, said strip having a curving lower portion, a cradle carried by the curve of the strip whereby the cradle is movable pivotally and lengthwise of said curved strip, and said cradle having an outer corner portion removed to permit the more convenient handling of the load of meat on the cradle.

JOHN C. GONSER.
